AGITATING MECHANISM

Herbert E. Preston, Philadelphia, Pa., assignor to
American Engineering Company, Philadelphia,
Pa., a corporation of Pennsylvania

Application August 16, 1935, Serial No. 36,513

8 Claims. (Cl. 259—38)

This invention relates to agitating mechanisms and more particularly to the agitating mechanisms employed in the fuel hoppers of stoker furnaces.

5 One object of the present invention is to provide a generally improved agitating mechanism which is operated directly by the fuel feeding elements of a mechanical stoker.

Another and more specific object is to provide 10 agitating levers in the fuel hopper of a stoker furnace adjacent each of the main fuel feeding rams thereof and to oscillate said levers by mechanism connected directly to said rams, to prevent arching of the fuel in the hopper and thus insure 15 at all times a uniform distribution of the fuel fed to the stoker by said rams.

Other and further objects will become apparent as the description of the invention progresses.

Of the drawings:

20 Fig. 1 is a side elevational view partly in section of the front end of a stoker furnace showing my improved agitating mechanism.

Fig. 2 is a sectional plan view taken substantially along line 2—2 of Fig. 1.

25 Fig. 3 is a sectional elevational view of the front end of the stoker taken substantially along line 3—3 of Fig. 2, and

Fig. 4 is a sectional elevational view taken 30 through a fuel hopper, showing an agitating mechanism of a modified type.

Referring to the drawings, the numeral 1 designates generally a stoker which comprises in the present instance a series of fuel feeding rams 2 operating in cylinders 3 mounted adjacent 35 the outer side of the front wall 4 of the furnace. Each ram 2 is hollow in construction and has pivotally connected internally thereof one end of a link 5, the other end of which is pivotally connected to the upper arm 6 of a three-arm lever 7 pivoted on a shaft 8 mounted in a bracket 9 secured in any suitable manner to the front end of the cylinders 3 and the supports 10 therefor. Another arm 11 of lever 7 has pivotally 40 connected thereto the lower end of a link 12, the upper end of which being pivotally connected 45 to a crank shaft 13 constituting the drive shaft of the stoker. Crank shaft 13 is operated by any suitable power mechanism indicated generally at 14.

50 Each ram cylinder 3 is secured to the front wall 4 of the furnace in any suitable manner and has an opening 15 provided at the upper end thereof which communicates with a discharge opening 16 of a fuel hopper 17. The substantially flat alternately disposed fuel supporting portions 18 of the hopper rest upon the flat lateral extensions 19 of the cylinders 3 and bolts 20 or other suitable securing means extending through these portions, and extensions rigidly 55 secure the hopper in position.

The left hand end (Fig. 1) of each cylinder 3 communicates with an opening 21 provided in the front wall 4 which constitutes the inlet to the fuel retorts of the stoker (not shown). Thus upon each reciprocation of the rams 2 predetermined quantities of fuel gravitating in the cylinders 3 from hopper 17 are fed to the stoker. 5

It frequently happens that arching of the fuel occurs over the discharge openings of the hopper which prevents a free movement of the fuel into 10 the cylinders upon recession of the feeding rams. Unequal quantities of fuel are therefore fed to the stoker, and as a result the efficiency thereof is not only impaired, but damage to the grates may also occur. The present invention contemplates an improved agitating mechanism 15 which prevents the formation of such arches and insures proper movement of the fuel from the hopper to the feeding mechanism under all conditions of operation. 20

Referring more particularly to Figs. 1 and 2 of the drawings, it will be observed that a series of bell crank levers 22 are mounted near the bottom of the hopper. These levers are arranged in pairs and comprise an agitating arm 23 extending substantially parallel to one side of the corresponding discharge openings, and an operating arm 24. The levers 22 are pivotally supported upon bearing portions 25 integral with and extending outward of the front wall 17' of hopper 25 30 35 40 45 50 55 60 65 70 75 80 85 90 95 100 105 110 115 120 125 ing of the fuel in the hopper. The elongated slots 35 in rod 32 provide a lost motion connection to limit the swinging movement of levers 22.

Fig. 4 shows a somewhat modified construction comprising a pair of spaced agitating levers 41 and 42. These levers are secured to a vertical shaft 43 journaled in bearing brackets 44 and 45 provided on the hopper 46. Levers 41 also have transversely extending arms 47 operatively connecting the rams of the stoker by means of reciprocating rods 48 similar to the levers 22 previously described. Levers 41 and 42 also are provided with flanged portions 49 which increase the effectiveness of the device. Thus upon reciprocation of the rams, levers 41 and 42 will be simultaneously operated.

This construction is particularly desirable in the larger hopper constructions, especially when damp or powderous fuels are employed. Such fuels have a greater tendency to pack into solid masses than other fuels, and obviously require more agitation to insure proper movement thereof.

While the embodiments herein described are admirably adapted to fulfill the objects primarily stated, it is to be understood that the invention is not to be limited thereto since it may be embodied in other forms, all coming within the scope of the claims which follow.

30 What is claimed is:

1. In a device of the class described, the combination with a cylinder, of a feeding ram operative in said cylinder, a hopper having a discharge opening communicating with said cylinder, said discharge opening being so disposed that upon recession of said ram, fuel from the hopper will gravitate into said cylinder, a lever pivotally mounted for transverse movement above and to one side of said discharge opening for agitating the fuel in said hopper, and means operatively connecting said lever to said ram.

2. In a device of the class described, the combination with a cylinder, of a fuel feeding ram operative in said cylinder, a hopper having a discharge opening communicating with said cylinder, agitating means provided in said hopper comprising one or more oscillatory levers, an actuating arm secured to said levers, reciprocatory means operatively connected to said arms for oscillating said levers, and means operatively connecting said reciprocatory means to said ram, said last mentioned means including a lost motion connection for limiting the oscillatory movement of said levers.

3. In a device of the class described, the combination with a cylinder, of a feeding ram operative in said cylinder, a hopper mounted above said cylinder and having a discharge opening communicating with said cylinder, said discharge opening being so disposed that upon recession of the ram fuel from said hopper will gravitate into said cylinder, agitating means provided in said hopper comprising a pair of vertically spaced levers, an actuating arm provided on one of said levers, reciprocatory means operatively connected to said arm for oscillating said lever, and means operatively connecting said reciprocatory means to said ram.

4. In a device of the class described, the combination with a cylinder, of a feeding ram operative in said cylinder, a hopper mounted above said

cylinder having a discharge opening communicating with said cylinder, said discharge opening being so disposed that upon recession of the ram fuel from said hopper will gravitate into said cylinder, agitating means provided in said hopper comprising a pair of vertically spaced levers, an arm provided on one of said levers, reciprocatory means operatively connected to said arm for oscillating said levers, and means operatively connecting said reciprocatory means to said ram, said last mentioned means including a lost motion connection for limiting the oscillatory movement of said levers.

5. In a device of the class described, the combination with a series of cylinders, of a fuel feeding ram operative in each of said cylinders, a hopper disposed above said cylinders having a series of discharge openings provided in the bottom thereof, one of said discharge openings communicating with each of said cylinders, supporting means for the fuel provided in the bottom of said hopper between said discharge openings, a front wall for said hopper, a plurality of agitating members extending through said front wall and overlying said fuel supporting means, means for pivotally supporting said members for transverse movement exteriorly of said front wall, and means operatively connecting said agitating members to said rams.

6. In a device of the class described, the combination with a cylinder, of a fuel feeding ram operative in said cylinder, a hopper having a discharge opening communicating with said cylinder, a front wall for said hopper, one or more horizontally disposed agitating members extending through said wall and lying adjacent said discharge opening, means for pivotally supporting said members for transverse movement, an operating arm for each of said members disposed exteriorly of said front wall, and means operatively connecting said operating arms to said ram.

7. In a device of the class described, the combination with a cylinder, of a fuel feeding ram operative in said cylinder, a hopper having a discharge opening communicating with said cylinder, a front wall for said hopper, one or more horizontally disposed oscillatory members extending through said front wall and lying adjacent said discharge opening, means for pivotally supporting said members for transverse movement, an actuating arm for each of said oscillatory members disposed exteriorly of said front wall, reciprocatory means operatively connected to said arms, and means operatively connecting said reciprocatory means to said ram.

8. In a device of the class described, the combination with a cylinder, of a fuel feeding ram operative in said cylinder, a hopper having a discharge opening communicating with said cylinder, a front wall for said hopper, a pair of vertically spaced and horizontally disposed agitating levers extending into said hopper and lying adjacent said discharge opening, means for pivotally supporting said levers for transverse movement, an operating arm secured to one of said levers and disposed exteriorly of said front wall, and means operatively connecting said operating arm to said ram, whereby upon operation of the latter an oscillatory movement is imparted to said agitating levers.

HERBERT E. PRESTON.
